US0D1000986S

(12) **United States Design Patent** (10) **Patent No.:** **US D1,000,986 S**
(45) **Date of Patent:** **** Oct. 10, 2023**

(54) **FRAME FOR SHIELDING ASSEMBLY**

(71) Applicant: **Laird Technologies, Inc.**, Chesterfield, MO (US)

(72) Inventors: **James D. Pille**, Ashley, IL (US); **Gerald R. English**, Glen Ellyn, IL (US); **Timothy M. Wrona**, Schaumburg, IL (US)

(73) Assignee: **Laird Technologies, Inc.**, Chesterfield, MO (US)

(**) Term: **15 Years**

(21) Appl. No.: **29/781,612**

(22) Filed: **Apr. 30, 2021**

Related U.S. Application Data

(62) Division of application No. 29/745,216, filed on Aug. 4, 2020, now Pat. No. Des. 919,626, which is a division of application No. 29/665,695, filed on Oct. 5, 2018, now Pat. No. Des. 895,623.

(57) **CLAIM**

We claim the ornamental design for the frame for shielding assembly, as shown and described.

DESCRIPTION

FIG. 1 is an upper perspective view of a frame for a shielding assembly showing our new design;

FIG. 2 is a lower perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a left side elevation view thereof; and,

FIG. 8 is a right side view thereof.

In the drawings, the details shown in broken lines depict environmental subject matter only and form no part of the claimed design.
